UNITED STATES PATENT OFFICE.

THOMAS J. LYNCH, OF MARIETTA, PENNSYLVANIA.

SERUM CONTAINER AND INJECTOR.

SPECIFICATION forming part of Letters Patent No. 740,152, dated September 29, 1903.

Application filed November 8, 1902. Serial No. 130,546. (No model.)

To all whom it may concern:

Be it known that I, THOMAS J. LYNCH, a citizen of the United States, residing at Marietta, in the county of Lancaster and State of Pennsylvania, have invented a new and useful Serum Container and Injector, of which the following is a specification.

My invention consists of a serum container and injector, and it is devised particularly for use in the dissemination and application of diphtheritic antitoxin. It should be understood, however, that the invention may be used for other serums or for other medicines used hypodermically. In all cases where serums are hypodermically injected it is of the utmost importance that the serum itself should not be exposed to the air or other contaminating influences between the time it is put up at the laboratory and that of use. It is equally important that the injecting instrument should be sterile.

It is now customary to distribute serums in glass receptacles hermetically sealed and each containing sufficient serum for one injection and to open such containing-receptacle by breaking a narrow neck of the container. There is more or less danger incident to this practice due to the fact that minute particles of the glass may become mixed with the serum or in some way be introduced into the syringe, and thence into the wound, causing subsequent trouble. My invention seeks to guard against all of these dangers; and it consists of a container for the serum which is never opened to the air between the time it is filled and when it is emptied at the time of making the injection; and it further consists of means combined with such container which constitute a hypodermic syringe all of which parts may be sterilized and kept in a sterilized condition until the moment of use.

In the accompanying drawings, wherein the preferred form of my invention is illustrated, Figure 1 is a side view of the complete instrument, comprising the container and parts combined therewith to make a hypodermic syringe. Fig. 2 is a longitudinal sectional view. Fig. 3 is a detached view of the serum-container. Fig. 4 is a detached view of the hypodermic needle.

In the views the parts are indicated as considerably enlarged.

In the drawings, A designates a body of tubular form open at each end, adapted to contain the serum. The open ends of this body are hermetically closed by stoppers B, composed of some material that may be sterilized and may also be penetrated by a needle such as is used for hypodermic injections. The container such as described, consisting of the body A, which is usually formed of glass, and the stoppers B, closing its opposite ends, is filled at the laboratory with a certain definite amount of the serum—an amount sufficient to be used for a single injection. With each one of these containers I provide a hypodermic needle C. I prefer that the needle C should be of the peculiar construction illustrated in the drawings—that is, having its opposite ends *c c* pointed and being provided intermediate the pointed ends with a grasping enlargement *c'*, the edge of which may be milled. Such needle after being carefully wrapped in cotton and paper is sterilized, in which wrapped condition it is kept until an injection is to be made, when the operator grasps the needle by the enlargement *c* and forces it through the cork or stopper in one end of the container A. This may be done before the wrapping that surrounded the needle is removed. The needle will now occupy the position indicated in Figs. 1 and 2, one pointed end projecting through the stopper and into the fluid. I prefer that the inner face of the stopper, through which this needle is inserted, should be made concave, as indicated at *b*, in order to form a depression in which the last drop of the serum may collect around the exposed inner end of the needle in order to prevent any waste thereof. In order to expel the serum from the container, I employ an air-bulb D, that is secured to the end of a hollow needle E, the end *e* of which is pointed like the ends of the needle C, thereby adapting it to be passed through the stopper situated at the end of the serum-container opposite to that through which the needle C has been passed. It will be understood that one of these bulbs and its attached needle are supplied with each container and that the needle E is thoroughly sterilized before it is inserted through the cork or stopper B. When the parts are assembled as indicated in Fig. 1, a

hypodermic syringe is produced and the body or fluid-containing portion A of which is the same receptacle as that in which the fluid was originally placed at the laboratory. It will 5 also be observed that it is not necessary to break any part of the glass container in order to connect the injecting-needle or the expelling-bulb, nor is it necessary to expose the contents of the container to the air or to any 10 contaminating object before the injection is made.

By using an elastic material, such as rubber, for the stoppers B, I not only employ material that may be sterilized and that will hermetically close the container A, but I secure 15 a flexible support for the hypodermic needle which permits a certain freedom of movement thereof, as indicated by dotted lines in Fig. 1. It is desirable to secure this freedom of movement because the patient often moves when 20 an injection is being made, and this flexibility will prevent injury to the patient or displacement of the needle.

By forming the openings through the necks 25 of the container so that they each have a portion that flares or expands inward, as represented clearly in Fig. 2, and employing therewith flexible stoppers I insure that the stoppers shall maintain their positions in the 30 necks of the container, as after being forced into place the inner portions of the stoppers expand. In order to facilitate the inserting of the stopper in the neck of the container when thus constructed to flare or expand inward, I prefer to also flare or expand the neck 35 in an outward direction beyond the most contracted part.

I prefer that the container should be of the shape shown—that is, of cylindrical form and 40 substantially uniform in diameter throughout, except at the ends, where the tube is slightly contracted to form necks which operate to securely hold the stoppers in place. It may, however, be of different shape—as, 45 for instance, of bulb form, with tapering ends or necks.

By forming the corks or stoppers with the 50 enlarged flanges or heads that are adapted to bear against the ends of the container, as represented in the drawings, I provide against danger of the stoppers being forced into the container when the perforated tubes or needles are forced through such stoppers.

While it is my intention that the parts of 55 the syringe which I have described should be used but once, thus reducing to a minimum the danger of infection from the use of a needle which has been before employed and has not been properly sterilized, yet I do not 60 limit my invention to such use, as all of the parts of the syringe are adapted for repeated use and may be so used if found desirable.

Having described my invention, what I 65 claim, and desire to secure by Letters Patent,

stances to be administered hypodermically, consisting of a tubular body open at both ends, the open ends of the container being formed with necks constructed to flare or expand inwardly, stoppers for hermetically closing the open ends of the body constructed of yielding elastic material that may be penetrated by a needle and formed with enlarged or flanged heads arranged to bear against the edges of 70 the necks of the body to prevent the stoppers being forced into the interior of the container when a needle is forced through them, substantially as set forth.

2. A container for serums and like substances to be administered hypodermically, 80 consisting of a tubular body open at both ends and provided at its open ends with contracted necks constructed to flare both inwardly and outwardly, and stoppers fitting the said necks 85 for hermetically closing the body, formed of a yielding, elastic material that may be penetrated by a needle, and formed with enlarged or flanged heads arranged to bear against the outer edges of the necks of the body, substantially 90 as set forth.

3. In a hypodermic injector, the combination of a container for the fluid having one end hermetically closed by a stopper, and a hollow needle having one end adapted to be 95 inserted beneath the skin of the patient and its opposite end adapted to be forced through the said stopper into the interior of the container, and means for forcing the fluid from the container through the said needle, substantially 100 as set forth.

4. In a hypodermic injector, the combination of a container for the fluid having one end closed by a stopper adapted to be penetrated, a double-pointed needle C, one pointed 105 end of which is passed through the said stopper, and means for forcing the fluid from the container through the said hollow needle, substantially as set forth.

5. A needle for use in making hypodermic 110 injections having opposite pointed ends c, c', and the intermediate enlargement c' by which the needle may be grasped and manipulated, substantially as set forth.

6. In a hypodermic injector, the combination of a body in which the fluid is contained having an open end hermetically closed by a flexible stopper B, and the hypodermic needle passing through the said stopper into the interior of the container, and means for forcing the fluid from the container through the needle, substantially 115 as set forth.

7. In a hypodermic injector, the combination of a container for the fluid, a hypodermic needle through which the fluid is ejected, a 120 stopper closing one end of the container, an air-bulb, and a hollow tube connected with the air-bulb arranged to be passed through the said stopper and forming an air-duct between the air-bulb and the interior of the container, substantially as set forth.

8. In a hypodermic injector, the combina-

1. A container for serums and like sub-

tion of the glass body A adapted to contain the fluid to be injected, the rubber stoppers B, B, closing the opposite ends of the body A, the double-pointed needle C passing through 5 one of the stoppers into the container A, the hollow needle E passing through the other stopper into the interior of the container, and

the air-bulb connected with the outer end of the needle E, substantially as set forth.
